UNITED STATES PATENT OFFICE.

MAX KRONSTADT, OF BROOKLYN, NEW YORK, ASSIGNOR TO BRISTOL SEAMLESS RING COMPANY, OF NEW YORK, N. Y.

DESIGN FOR A RING.

Application filed February 2, 1926. Serial No. 16,370. Term of patent 14 years.

To all whom it may concern:

Be it known that I, MAX KRONSTADT, a citizen of the United States of America, residing in Brooklyn, county of Kings, in the city and State of New York, have invented a new, original, and ornamental Design for a Ring, of which the following is a specification, reference being had to the accompanying drawing, forming part thereof.

Figure 1 is an edge view of a ring constituting my new design;

Figure 2 is a side view thereof; and

Figure 3 is a section taken on the line 3—3 of Figure 2.

I claim:

The ornamental design for a ring, substantially as shown.

MAX KRONSTADT.
